UNITED STATES PATENT OFFICE.

WALTER VAN GUILDER, OF CHICAGO, ILLINOIS, ASSIGNOR TO STEWART-WARNER SPEEDOMETER CORPORATION, OF CHICAGO, ILLINOIS, A CORPORATION OF VIRGINIA.

SPEED-INDICATING INSTRUMENT.

1,353,865.

Specification of Letters Patent. Patented Sept. 28, 1920.

Application filed June 17, 1918. Serial No. 240,555.

To all whom it may concern:

Be it known that I, WALTER VAN GUILDER, a citizen of the United States, residing at Chicago, in the county of Cook and the State 5 of Illinois, have invented certain new and useful Improvements in Speed-Indicating Instruments, of which the following is a specification, reference being had to the accompanying drawings, forming a part 10 thereof.

The purpose of this invention is to provide an improved construction of speed indicating device having the magnet fixed,—that is, non-rotating, the rotating element 15 being a multi-polar armature which may be comparatively light, thereby adapting the instrument for indicating the speed of shafts to be rotated by light power, and whose speed of rotation would be materially 20 reduced by the resistance of a speed indicating device having heavy parts to be rotated. It consists in the elements and features of construction shown and described as indicated in the claims.

25 In the drawings:

Figure 1 is an axial section of an instrument embodying this invention.

Fig. 2 is a front elevation of the same with the cover member removed.

30 Fig. 3 is a section at the line, 3—3, on Fig. 1.

Fig. 4 is a section at the line, 4—4, on Fig. 1.

The instrument shown in the drawings 35 comprises a casing, 1, in which there is supported rigidly a magnet mount, 2, which is made of non-magnetic metal in the general form of a cup having at the top edge or front edge an outwardly-extending flange, 40 a, by which the mount is supported on the casing. The magnet element comprises two semi-annular magnets, 4, 4, which are fitted within the cup-shaped mount, being lodged upon the bottom or back diaphragm thereof 45 and against the circular wall, said magnets while called semi-annular, being in fact each slightly less than a half circle, so that when they are positioned as stated in the cup, two equal inter-polar gaps exist, said 50 magnets being placed with their poles of opposite name respectively facing each other at opposite sides of said gaps. Said mount is preferably a casting and formed

with inwardly-extending radial projections 2^a, 2^a, from its annular wall, entering the 55 inter-polar gaps between the two magnets as stated, and thereby further securely position the magnets in the mount. For further securing the magnets in the mount there is provided an annular retaining plate 5, 60 which is peripherally engaged with the annular wall of the mount, being positioned at the opposite side of the magnets from the bottom web of said mounts. For assembling the parts as described and engaging 65 the annular retaining plate, 5, peripherally with the cup-shaped mount as described, the retaining plate has any convenient number,—as shown, two diametrically opposite each other,—of peripheral projections, 5^a, 70 and the mount has two correspondingly situated notches, 2^b, 2^b, extending in from its open edge a short distance, each connecting with a groove, 2^c, formed in the inner wall of the cup-shaped mount; so that said retaining plate may be introduced into position by entering its said projections through 75 said notches to the bottom thereof, and then rotating the plate to engage the projections with said grooves, as seen in Fig. 2. On 80 the back wall of the case, 1, there is mounted an inwardly-projecting bearing stud, 7, on which there is journaled a gear, 8, which is conveniently retained on the stud by a cap screw, 9. This gear carries a multi-polar 85 armature, 12, at the center of which it is secured to said gear for rotation thereby. As shown, the armature has an even number of poles, equally spaced, so that the relation of the poles to the two diametrically-opposite inter-polar gaps of the magnet are at 90 all times identical; that is to say, the sum of the distances of the armature poles from the center of the two inter-polar gaps respectively of the magnets are at all times 95 the same, so that balanced torque is at all times obtained. Intermediate the fixed magnets and the rotating multi-polar armature, there is positioned an electrically conductive drag element, 15, which is a disk 100 mounted upon a spindle, 16, for which bearings are obtained at the side toward the armature by means of a cross-bar, 17, mounted upon the magnet mount, 2, and at the opposite side by a rigid arm, 18, also mounted 105 upon the magnet mount. In these supports,

17 and 18, there are provided suitable jeweled bearings, 17^a and 18^a, for the opposite ends of the spindle, 16. For the sake of compactness the drag element of the drag 5 disk is depressed at its central part so that it is secured to its spindle between the planes of the opposite sides of the magnet element, that is to say, in the central space of the annular structure comprising said two semi- 10 annular magnets. A dial plate, 20, is mounted upon the magnet mount, having a central opening through which the spindle extends for carrying in front of said dial plate an index pointer, 21, mounted on the spindle back of the spindle bearing in the arm, 18. The front of the case may be closed 15 by a cover, 25, comprising a transparent crystal, 26, through which the reading of the instrument may be observed. For rotating the rotatable armature there is journaled in the case a shaft, 28, having at its inner end a gear, 27, meshing with the gear, 8, the outer end of said shaft being adapted 20 for driving connection in a manner which 25 will be understood from the drawings without explanation.

For calibrating the instrument there is mounted in relation to each of the semi-annular magnets a shunt terminal pole piece, 30, of soft iron which is conveniently formed 30 angle shaped as seen at Fig. 2, having one flange provided with a slot, 31, by which the pole piece is adjustably mounted upon the ring, 5, by means of a screw, 32. The 35 range of adjustment of the pole piece with respect to the magnet is such as to permit the flange, 33, of the shunt terminal, 30, to project more or less across the inter-polar gap of the magnet, and thereby be adapted 40 to conduct a larger or lesser portion of the flux across the gap, for diminishing the amount of flux which is diverted by the poles of the rotating multi-polar armature through the drag element, thereby varying 45 the drag effect. This, it will be seen, will enable the assembler of the machine to make such adjustment as may be necessary to cause a given speed to produce a given indication upon the dial, notwithstanding variation 50 in the strength of the magnets, and variation in the resistance of the biasing spring. That is to say, it facilitates adaptation of the biasing spring to the strength of 55 the magnets, by modification of the proportion of the magnet-strength which becomes effective for producing drag.

For the purpose of adopting the instrument to be automatically compensated for temperature changes and also to automatically compensate 60 for changes in the magnet strength the interpolar gaps between the magnets, which as stated are in the main occupied by the substance of the mount, which has the projections, 2^a, for engaging said interpolar 65 gaps to position the magnets fixedly are

partly opened by cutting away the material of the mount in angular form as seen at 2^d, and for each gap there is provided an angular or V-shaped soft iron armature piece, 35, mounted upon one end of the bi-metallic 70 spring carrying arm, 36, the other end of which is secured to the mount, so that said soft iron armature piece may protrude more or less deeply into the interpolar gap according to the curvature of the bi-metallic 75 arm which carries the armature, which is effected by the change of temperature. The member of the bi-metallic arm having the higher coefficient of expansion being on the inner side, as the temperature rises the arm 80 will be straightened with the effect of carrying the armature piece back out of the gap, and when the temperature falls it will be more curved, carrying said armature piece toward or into the gap; which it will be 85 understood will have the effect of diverting a larger amount of the magnetic flux from the rotating armature as the temperature falls, and permitting a larger portion of the flux to be diverted by the rotating armature 90 so as to be cut by the drag element as the temperature rises; thus compensating for the diminution of drag which results from the rising temperature and the increase 95 which results from the falling temperature. 95

The arms, 36, being as stated, spring arms, are adapted to yieldingly resist the tendency of the V-shaped armature, 35, to move toward the magnet poles under the attraction of the magnet; and upon any decrease in 100 the magnet's strength, the armature piece, 35, will be retracted by the spring arm away from the magnet poles, thereby diminishing the proportion of the magnetic flux passing through said armature piece, 35, and correspondingly increasing the proportion of flux passing through the poles of the revolving armature, 12. Similarly, any increase in the magnet's strength causing the armature piece, 35, to approach the magnet poles, diminishing the proportion of flux passing 105 through the revolving armature. It will be understood that these changes of proportion of flux passing through the revolving armature, correspondingly affects the drag on the 110 drag element, 15, increasing the drag relatively upon decrease of magnet strength, and decreasing it relatively upon increase of magnet strength, thus automatically compensating for such changes in magnet 115 strength. 120

I have indicated that the device described has two interpolar gaps and a rotating armature provided with an even number of poles; but it will be obvious that the result 125 sought by this feature of the construction requires only that the number of armature poles be a multiple of the number of magnet gaps, there being a plurality of said gaps. The preferred number of gaps being 130

two, there will be an even number of armature poles, as specifically shown and described.

I claim:—

5. 1. In a magnetic speed indicating instrument in combination with a non-rotating magnet; the multi-polar armature device mounted for rotating its poles past the magnet poles; an electrically conductive drag 10 disk positioned and pivotally mounted for oscillation in a plane intermediate the magnet poles and the path of rotation of the armature poles, and means for biasing the disk in respect to the direction of its oscillatory movement; the magnet element comprising a plurality of equally-dimensioned magnets each having both its poles in the same plane transverse to the axis of rotation of the armature device, and the poles 15 of each proximate respectively to the oppositely-named poles of another, for forming in a circle about said axis as many inter-polar gaps between poles of opposite names of different magnets, as the entire number 20 of magnets of the magnet device; the mount for the magnet consisting of a non-magnetic substance encompassing and occupying the inter-polar gaps of said magnets, and a lateral annular retaining plate at one side of 25 the magnets peripherally engaged with said mount.
2. In the structure defined in claim 1 foregoing, the mount having a bayonet-lock slot and the plate having a peripheral projection adapted to be entered through and engaged with said bayonet lock slot by angular movement of the plate, for securing the magnet against displacement of the mount.
3. In a magnetic speed indicating instrument comprising a fixed magnet element having an inter-polar gap; a revolving interrupted armature, and a drag element intermediate the magnet and said armature; a 35 temperature compensating device consisting of a soft iron armature piece and a bi-metallic arm which carries said armature piece on its movable end proximate to the inter-polar gap of the magnet for moving it relatively to said gap upon temperature changes deflecting said bi-metallic arm.
4. In a magnetic speed indicating instrument comprising a fixed magnet element having an inter-polar gap, a revolving interrupted armature, and a drag element intermediate the magnet and said armature; a 45 calibrating device consisting of an adjustable pole piece or shunt terminal mounted adjacent to one pole of the magnet and adjustable relatively thereto toward and from the other pole across the inter-polar gap.
5. In a magnetic speed indicating instrument such as defined in the last claim foregoing, the magnet element comprising a plurality of arcuate elements positioned in the same plane with substantially equal inter-polar gaps, one of the magnet poles at each gap being provided with the adjustable pole terminal or shunt.
6. In a magnetic speed indicating element 70 in combination with a magnet element having an inter-polar gap, a temperature compensating element consisting of a soft iron armature and a temperature-responsive carrier for the same mounted at one point 75 fixedly with respect to the magnet and carrying the soft iron armature at a point on said carrier which moves responsively to temperature change and at a position for moving in one direction toward both magnet poles and in the opposite direction away from both magnet poles.
7. In a construction such as set out in claim 6 foregoing, the armature carrier being a bi-metallic arm.
8. In a device such as defined in claim 6, the compensating armature carrier being a bi-metallic arm, mounted at one end fixedly with respect to the magnet and carrying the armature at the other end in the plane 90 of the magnet toward and from the inter-polar gap.
9. In a magnetic speed indicating instrument in combination with a magnet element, a drag element and a flux-deflecting armature for deflecting the flux through the drag element, a magnet-strength-change-compensating device comprising a soft iron armature element positioned proximately to the magnet gap and a spring support for the 95 same mounted for yielding toward both poles in one movement and reacting away from both poles in the opposite movement.
10. In a structure such as defined in claim 9 foregoing, the magnet being fixed and the flux-deflecting armature being multi-polar, positioned laterally with respect to the magnet and rotating, and the compensating armature being carried by the spring support for movement radially toward and away from the inter-polar gap of the magnet.

In testimony whereof, I have hereunto set my hand at Chicago, Illinois, this 14th day of June, 1918.

WALTER VAN GUILDER.
